[57] CLAIM

The ornamental design for an electrostatic voltage measuring instrument, as shown and described.

DESCRIPTION

FIG. 1 is a right side elevational view of an electrostatic voltage measuring instrument showing my new design, the left side being a mirror image thereto;

FIG. 2 is a top plan view thereof;

FIG. 3 is a bottom plan view thereof;

FIG. 4 is a front elevational view thereof, and

FIG. 5 is a rear elevational view thereof.
